UNITED STATES PATENT OFFICE.

JOHN F. O'CONNOR, OF CHICAGO, ILLINOIS, ASSIGNOR TO PRATT AND LETCHWORTH COMPANY, OF BUFFALO, NEW YORK, A CORPORATION OF NEW YORK.

TRUCK-BOLSTER FOR RAILWAY-CARS.

1,243,757.

Specification of Letters Patent. Patented Oct. 23, 1917.

Application filed February 26, 1914. Serial No. 821,298.

To all whom it may concern:

Be it known that I, JOHN F. O'CONNOR, a citizen of the United States, residing in Chicago, in the county of Cook and State of Illinois, have invented a new and useful Improvement in Truck-Bolsters for Railway-Cars, of which the following is a specification.

This invention relates to improvements in 10 bolsters and more particularly to truck bolsters for railway cars.

Objects of the invention are to provide a bolster of the type specified which consists of two steel castings of substantially like 15 form which may be cast without the use of cores; to provide a cast steel bolster of strong and serviceable construction which may be easily cast and having a pattern which may be easily drawn from the molds; 20 and to provide a cast steel bolster composed of two like parts securely riveted together and each of which is substantially channel-shaped in cross section.

The invention furthermore consists in the 25 improvements in the parts and devices and in the novel combination of the parts and devices as herein shown, described or claimed.

In the drawing forming a part of this 30 specification Figure 1 is a top plan view of one form of bolster embodying my improvements. Fig. 2 is a side elevation of the structure shown in Fig. 1 and Figs. 3 and 4 are vertical, enlarged sectional views taken 35 substantially on the lines 3—3 and 4—4, respectively, of Fig. 2.

In said drawing, the bolster proper is designated generally by the reference A and, as shown, comprises two substantially like 40 members B each a steel casting and forming substantially a vertical half of the bolster. Each member B is substantially channel-shaped in cross section, as shown most clearly in Figs. 3 and 4, and comprises a vertically extending web 10, upper flange 11 and lower flange 12, the upper flange 11 being straight from end to end and the lower flange having upwardly inclined portions 13 and outer horizontal end 45 portions 14. Each member B, at its ends, is provided with horizontally extending centrally located flanges 15 having straight outer edges 16 and diagonally extending inner edges 17.

As shown most clearly in Fig. 3, the

flanges 15 overlap when the two members are assembled and are rigidly and permanently secured together by a plurality of rivets 18. The upper flanges 11 of the members B are cut away above the overlapped flanges 15, as shown at 19, and the lower flange portions 14 are likewise cut away, as shown at 20, to thereby provide clearance when heading or upsetting the rivets. Each member B, at its ends, is provided with 60 integral guiding ribs 30, 30 for members of the truck (not shown), and on its inner side is provided with a plurality of vertically extending strengthening ribs 21, 21. Each member B also has its upper flanges cut 65 away slightly at the center as shown at 22 to receive ribs 122 on the center bearing plate 23, shown in Fig. 1 in full lines and in dotted lines in Fig. 2. Near the ends of the bolster there are secured thereto side 70 bearing brackets 33, 33 which may be of 75 any well known or desirable construction.

From the preceding description it will be seen that the two members of the bolster are of substantially identical construction and 80 may be cast without the use of cores. The bolster members are also so designed that it is an easy matter to make the molds therefor, since the pattern may be readily withdrawn 85 from the mold inasmuch as the pattern will be substantially entirely located within the drag of the flask, the only portions of the pattern which extend into the cope being the parts corresponding to the ribs 30. The bolster is furthermore so constructed that it 90 has all straight lines, a desirable feature, and is practically of girder-like construction, with the fastening devices or connections located wholly within the confining walls 95 of the bolster.

Although I have herein shown and described what I now consider the preferred embodiment of my improvements, yet it will be understood that various changes and modifications may be made without departing from the spirit of the invention, and all such changes and modifications are contemplated as come within the scope of the claims appended hereto.

With the construction which I have provided, it will be noted that when the trucks are in service, the upper horizontal flanges or portions 11, 11 are placed under compression and the inclined lower flanges or portions 13, 13 are placed under tension, 105 110

these forces being exerted in straight lines and therefore in the most efficient manner. When this action takes place, the upright members 21, 21 act as struts to prevent the tendency of said portions to collapse. Hitherto, in some forms of cast steel bolsters, where the upper and lower members are curved or bulged, there is a certain tendency for those portions under compression to buckle and those under tension to straighten out, thus decreasing the rigidity and stability of the bolster. By designing the bolster as I have shown, these defects are eliminated.

15 I claim:

1. A bolster of the character described comprising two members of substantially channel-shape in cross section, each of which is provided with horizontally extending overlapped flanges at their ends riveted together, substantially as specified.
2. A bolster of the character described comprising two steel castings each of which

is substantially channel-shaped in cross section and provided with horizontally extending overlapped flanges at its ends, said flanges being riveted together, substantially as specified.

3. A bolster of the character described comprising two members of like construction each of which is substantially channel-shaped in cross section and provided with centrally located horizontally extending flanges at its ends, said flanges being overlapped and riveted together, the upper and lower flanges of such channel-shaped members being cut away above and below said overlapped riveted flanges, substantially as specified.

Signed this 14th day of February, 1914, in 40
the presence of two witnesses.

JOHN F. O'CONNOR.
